M. E. AXTELL.

SIGN BOARD.

APPLICATION FILED OCT. 26, 1915.

Patented May 29, 1917.

UNITED STATES PATENT OFFICE.

MANLY E. AXTELL, OF VICKSBURG, MICHIGAN.

SIGN-BOARD.

1,227,989.

Specification of Letters Patent. Patented May 29, 1917.

Application filed October 26, 1915. Serial No. 57,923.

To all whom it may concern:

Be it known that I, MANLY E. AXTELL, a citizen of the United States, residing at Vicksburg, county of Kalamazoo, and State 5 of Michigan, have invented certain new and useful Improvements in Sign-Boards, of which the following is a specification.

This invention relates to improvements in sign boards.

10 The main objects of my invention are:

First, to provide an improved sign board constructed of metal which may be shipped or transported in the knock-down and quickly and easily assembled at the place of 15 erection.

Second, to provide an improved metal sign board which may be constructed of comparatively light material and is at the same time rigid and durable and one which 20 is economical to produce.

Further objects, and objects relating to details and economies of construction and operation will definitely appear from the detailed description to follow.

25 I accomplish the objects of my invention by the devices and means described in the following specification. The invention is illustrated in the accompanying drawing forming a part of this specification, in 30 which:

Figure I is a side elevation of my improved sign board, the same being illustrated as set in the ground.

Fig. II is an edge view thereof.

35 Fig. III is an enlarged detail horizontal section on a line corresponding to line 3—3 of Fig. I showing structural details of the standards or uprights and the manner of securing the panel thereto.

40 Fig. IV is an enlarged detail vertical section on a line corresponding to line 4—4 of Fig. II, showing further structural details of the manner of securing the panel.

Fig. V is an enlarged detail vertical section on a line corresponding to line 5—5 of 45 Fig. I showing the manner of assembling and securing the top bar and the standard top members.

Fig. VI is a detail vertical section on a 50 line corresponding to the line 6—6 of Fig. I showing the details of securing the leg braces.

Fig. VII is a detail vertical section on a line corresponding to line 7—7 of Fig. I

showing further details of the standard 55 structure.

Fig. VIII is a detail elevation of one of the standards with one of the leg braces collapsed therein.

Fig. IX is a horizontal section on a line 60 corresponding to line 9—9 of Fig. I showing the arrangement of the braces.

In the drawing similar reference characters refer to similar parts throughout the several views, and the sectional views are 65 taken looking in the direction of the little arrows at the ends of the section lines.

Referring to the drawing, I provide a pair of standards 1, each formed of a pair of facing channel iron members 2. The 70 standard members have their upper portions parallel and their lower portions diverging to provide a pair of legs 3. The lower ends of the legs are connected by cross pieces 4 permanently secured by means of 75 the rivets 5. The standard leg portions are provided with braces 6. These braces are formed of bars folded into loops with the arms of the loops converging. See Fig. 80 VIII.

These braces are disposed diagonally and in a crossed relation one through the other and their ends secured between the diverging leg portions of the standards. The braces are arranged with their converging 85 ends upwardly, their upper ends being pivotally secured one to each standard at 7 so that when their lower ends are disconnected from the opposite standard they may be collapsed between the diverging leg 90 portions of the standard to which they are so pivotally connected. The bight ends 8 of the braces are secured by bolts 9 to the other standard and form cross pieces for the standard leg portions. This arrangement 95 permits the parts being shipped or transported or stored in the knockdown and when arranged for such transportation or storage the braces are secured by the pivots 7 and collapsed between the leg portions. When 100 the signs are erected the braces are arranged one through the other as shown and their bight ends secured by the rivets or bolts 9.

The parallel portions of the standard members 2 are connected by bolts 9'. The 105 panel 10 is disposed with its edges between the standard members, see Fig. III. The vertical edges of the panel have flanges 11

formed thereon which engage with the standard thereby preventing buckling of the panel and securely retaining its edges between the standard members.

5 A pair of bolts 9' are arranged below the bottom edge of the panel, see Fig. IV, and constitute supporting rests therefor. The remaining bolts 9 are arranged at the edges of the panel as shown in Fig. III, so that 10 the panel may be introduced by sliding from the upper ends of the standards, the bolts being merely loosened slightly to permit the introduction of the panel and after the 15 same is in place, they are tightened up to clamp the same.

I preferably provide a top piece 12 arranged above the panel with its ends clamped between the support members, see Fig. V. I also preferably provide the standards with top members 13 having shanks 14 inserted between the standard members and clamped therein. These standard top members may be in the form of arrows or indicators or other suitable ornaments as 25 desired.

With this arrangement of parts, the sign boards may be shipped in the knock-down and, if desired, conveniently assembled at the point of erection. When knocked down 30 the parts may be very compactly arranged. By forming the standards as I have illustrated and described, light material may be used and at the same time they are very 35 strong and rigid and have substantial legs or base portions for setting in the ground or in cement. The panels can be conveniently changed as occasion requires.

A further object of the structure is that by providing diverging leg portions and 40 connecting them with cross pieces at their lower ends, the sign is not heaved or raised from the ground by the action of frost.

Having thus described my invention, what I claim as new and desire to secure by 45 Letters Patent, is:

1. In a signboard, the combination of a pair of standards, each consisting of a pair of standard members having parallel upper portions and diverging leg portions, said 50 leg portions being connected by cross pieces at their lower ends, said parallel portions being connected by bolts disposed therethrough, leg braces formed of bars folded into loops with the arms of the loops converging, said braces being disposed one 55 through the other in a crossed relation and secured between the diverging leg portions of the standard, the upper end of each brace being pivotally secured so that they 60 may be collapsed between the said leg portions of the standard to which their upper ends are connected when their lower ends are disconnected from the other standard, and a panel supported between parallel portions of said standard.

2. In a signboard, the combination of a pair of standards, each consisting of a pair of standard members having parallel upper portions and diverging leg portions, said leg 70 portions being connected by cross-pieces at their lower ends, said parallel portions being connected by bolts disposed therethrough, leg braces formed of bars folded into loops with the arms of the loops converging, said braces being disposed one 75 through the other in a crossed relation with their ends secured between the diverging leg portions of the standard members, the bight ends of said braces constituting cross pieces for the standards to which they are 80 secured.

3. In a signboard, the combination of a pair of standards, each consisting of a pair of facing channel irons having parallel upper portions and diverging leg portions, 85 said parallel portions being connected by bolts disposed therethrough, and a panel having flanged vertical edges adapted to be introduced into said standards by sliding longitudinally from the upper ends thereof, 90 the connecting bolts for the parallel portions of said standard members at the lower ends of the panel being disposed under said panel and constituting rests therefor, the other bolts being disposed at the edges of 95 the panel and constituting means for clamping the standard members upon said panel.

4. In a signboard, the combination of a pair of standards, each consisting of a pair of facing channel irons having parallel portions connected by bolts disposed therethrough, a panel having flanged vertical edges adapted to be introduced into said standards by sliding longitudinally from the upper ends thereof, the connecting bolts 100 for the parallel portions of said standard members at the lower ends of the panel being disposed under said panel and constituting rests therefor, the other bolts being disposed at the edges of the panels and 105 constituting means for clamping the standard members upon said panel, a top bar disposed above said panel with its ends clamped between said standard members.

5. In a signboard, the combination of a 115 pair of standards, each consisting of a pair of standard members having parallel portions connected by bolts disposed therethrough, a panel arranged with its vertical edges between said standard members, the 120 connecting bolts for the parallel portions of said standard members at the lower ends of the panel being disposed under said panel and constituting rests therefor, the other bolts being disposed at the edges of the 125 panels and constituting means for clamping the upright members upon said panel, and a top bar disposed above said panel with its ends clamped between said standard members.

6. In a signboard, the combination of a pair of standards, each consisting of a pair of standard members having parallel portions connected by bolts disposed there-
5 through, and a panel arranged with its vertical edges between said standard members, the connecting bolts for the parallel portions of said standard members at the lower ends of the panel being disposed under said
10 panel and constituting rests therefor, the other bolts being disposed at the edges

of the panels and constituting means for clamping the upright members upon said panel.

In witness whereof, I have hereunto set 15 my hand and seal in the presence of two witnesses.

MANLY E. AXTELL. [L.S.]
